INFLATABLE CAR BED

Melvin L. Wieland, 3507 NE. 54th St.,
Kansas City, Mo. 64119

Filed July 8, 1971, Ser. No. 160,981

Term of patent 14 years

Int. Cl. D6—01

U.S. Cl. D6—201

Fig. 1.

Fig. 2.

Fig. 3.

Fig. 4.

Fig. 5.

FIG. 1 is a front elevational view of an inflatable car bed embodying my new design;

FIG. 2 is a top plan view thereof;

FIG. 3 is a rear elevational view thereof;

FIG. 4 is a bottom plan view thereof; and

FIG. 5 is a left side elevational view of an inflatable car bed with the opposite side being identical thereto.

I claim:

The ornamental design for an inflatable car bed, as shown and described.
